CLAIM

The ornamental design for a packaging box, as shown and described.

DESCRIPTION

FIG. 1 is a front, right and top perspective view of a packaging box, showing my new design;

FIG. 2 is a rear, left and bottom perspective view thereof;

FIG. 3 is an exploded view thereof;

FIG. 4 is another exploded view thereof;

FIG. 5 is a front side view thereof;

FIG. 6 is a rear side view thereof;

FIG. 7 is a left view thereof;

FIG. 8 is a right view thereof;

FIG. 9 is a top plan view thereof; and,

FIG. 10 is a bottom plan view thereof.

The broken lines shown in the drawings illustrate portions of the packaging box that form no part of the claimed design.

1 Claim, 10 Drawing Sheets
